UNITED STATES PATENT OFFICE.

BYRON REECE BEAVER, OF ULYSSES, NEBRASKA.

WRENCH.

Application filed April 8, 1925. Serial No. 21,649.

This invention relates to wrenches and more particularly to sliding jaw wrenches.

The object of the invention is to provide a wrench of this character, the jaws of which 5 may be quickly and easily set and when set will hold like a vise.

Another object is to provide a wrench of this character which will hold and turn to the right or left and will not drop off of 10 the object gripped when the hands are removed therefrom.

With the foregoing and other objects in view which will appear as the description proceeds, the invention resides in the combination and arrangement of parts and in the details of construction hereinafter described and claimed, it being understood that changes in the precise embodiment of 15 the invention herein disclosed may be made 20 within the scope of what is claimed without departing from the spirit of the invention.

In the accompanying drawings:—

Figure 1 represents a side elevation of a wrench constructed in accordance with this 25 invention with the jaws shown closed and in locked position, parts being broken out to illustrate obscure parts;

Fig. 2 is a similar view with the jaws in open position, ready to receive the object 30 to be gripped; and

Fig. 3 is a transverse section taken on the line 3—3 of Fig. 2.

In the embodiment illustrated the wrench constituting this invention comprises a handle 1 in the form of a metal bar sufficiently 35 heavy to withstand all strains to which it may be subjected and on the front end of which are riveted or otherwise fixedly secured two laterally spaced metal bars 2 and 3 to be secured to opposite faces of the handle member 1 as is shown clearly in Fig. 3 and which extend beyond opposite sides of said handle and are riveted or otherwise connected at their outer ends as shown at 4 and 40 4', the rivet 4' also operating as a fulcrum for a cam lever 10 to be hereinafter more fully described.

Slidably mounted between the bars 2 and 3 at opposite sides of the handle 1 are two 50 gripping jaws 5 and 6 having their inner faces cut out as shown at 7 to conform to the shape of the handle end in connection with which they are used, so that when the jaws are closed they will fit snugly around said handle. Beyond the cut out portions 7 on their meeting or opposed faces these jaws

are provided with straight gripping faces 8 at the inner ends of which are formed semi-circular toothed pipe or rod engaging recesses which when gripped around the pipe 60 or rod will securely hold it against turning.

The outer faces or edges of these jaws 5 and 6 are curved or rounded as shown at 11, said jaws gradually increasing in thickness or width from their inner ends toward 65 their center so that when they are moved inwardly to the position shown in Fig. 1 they will be moved toward each other by the engagement of their curved edges with connecting elements 4 and when so positioned 70 may be locked by engagement of a locking tooth or pawl carried by the free end of the lever 10 which is designed to engage with ratchet teeth 12 formed in the outer edge of jaw 6 near its inner end. This ratchet rack 75 12 may be of any desired length. This lever 10 which constitutes the locking means for the jaws is made in the form of a cam lever, the cam portion 14 of which is designed to engage the outer edge of jaw 6 when the 80 lever is in locked position as shown in Fig. 1, while the body portion of the lever is bowed outwardly and provided at its free end with an inturned tooth or spur 13 which constitutes the pawl for engaging the rack 12 for 85 locking said lever in adjusted position.

The inner or rear ends of the jaws 5 and 6 are pivotally connected with each other by links 15 and 16 arranged on opposite sides of the handle 1 and secured together 90 and to the jaws by rivets or pintles 17.

Two flat springs 18 are secured to the opposite edges of the handle 1 as shown clearly in Fig. 2 and exert their tension to normally force the jaws 5 and 6 apart so that when the 95 lever 10 is released the jaws will be opened by said springs.

It is of course understood that this wrench may be made of different sizes according to the work for which it is intended. 100

In the use of this wrench the jaws being shown in open position as illustrated in Fig. 2 they are placed over the object to be gripped thereby and the handle 1 moved forwardly causing the bars 2 and 3 and their connectors 4 to forcibly move said jaws toward each other into gripping engagement with the object between them and when they have been securely engaged with said object the lever 10 is swung into locking position 105 as shown in Fig. 1 and secured by engaging the tooth 13 thereof with the ratchet 110

rack 12. When in this position the article will be securely gripped and obviously the hands of the user may be removed from the wrench without its dropping from the object. 5 It may be turned either toward the left or the right according to the wishes of the user and when it is desired to release the object from the wrench the lever 10 is swung outwardly causing the cam head 14 thereof 10 to disengage jaw 6 which under the action of the springs 18 move outwardly into open position as shown in Fig. 2.

From the above description it will be obvious that a wrench constructed as herein 15 shown and described is cheap to manufacture and strong without any parts capable of being broken and should the springs 18 break or lose the resiliency they may be easily replaced.

20 I claim:—

A wrench including a handle portion, a pair of bars secured to the handle portion

adjacent to one end thereof, said bars being held in spaced relation by the handle portion, rivets connecting the bars adjacent to 25 their ends to close the ends of the bars, jaws having inclined outer edges and having their inner edges cut away to receive the handle portion, means for connecting the inner ends of the jaws to permit the jaws to 30 slide longitudinally of the handle portion, one of said jaws having teeth, a pivoted member having a cam portion at one end, carried by the bars and cooperating with the outer edge of one of the jaws for moving the 35 jaw associated therewith inwardly, said lever being curved, and the free end of said lever being formed into a tooth to engage the first mentioned teeth to hold the jaws in their positions of adjustment. 40

In testimony that I claim the foregoing as my own, I have hereto affixed my signature.

BYRON R. BEAVER.
